UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN-VALVE CONSTRUCTION

Application filed September 9, 1921. Serial No. 499,534.

This invention relates to an improved valve construction that is of especial utility in conjunction with by-product coke ovens; the invention has for an object to provide a valve, particularly of the mushroom type, which avoids leakages of gaseous media past the valve, when the valve is closed. A valve constructed in accordance with the invention has an important application in coking retort ovens designed for the employment of an extraneously-derived fuel gas, such as producer gas, whether the coke oven be of the combination type exemplified in the Letters Patent to Joseph Becker, No. 1,416,322, granted May 16, 1922, or of the ordinary "gas oven" type that is intended solely for the employment of an extraneously-derived gas, as the fuel.

In addition to the general objects recited above, the invention has for objects such other improvements and advantages in construction or operation, as are found to obtain in the structures and devices herein described or claimed.

In the accompanying drawings, forming a part of this specification and showing, for purposes of exemplification, a preferred form and manner in which the invention may be embodied and practiced, but without limiting the claimed invention to such illustrative instance or instances:

Figure 1 is a fragmentary sectional elevation of a by-product coking plant or battery, showing a portion of the mechanism for controlling the flow of the gaseous media through the flue and regenerative areas of the battery, said mechanism being equipped with an improved valve constructed in accordance with the present invention;

Fig. 2 is a top plan view of a flow box in which the valve is incorporated, portions of the mechanism being removed for the purpose of illustrating more clearly the construction of the flow box;

Fig. 3 is another top plan view of the flow box, showing the parts in the operative relation employed when the flow box is utilized for directing into a communicably connected regenerator an extraneously-derived gas, such as producer gas;

Fig. 4 is a vertical sectional view of the flow box and valve construction; and

Fig. 5 is an elevational view of the same.

The same characters of reference designate the same parts in each of the several views of the drawings.

In its present embodiment, the invention is especially designed for use in conjunction with the flow-control mechanism of a by-product coking plant, such as is illustrated in the accompanying drawings, and having general coke oven features exemplified in the prior Letters Patent of the United States of H. Koppers, Serial No. 818,033, dated April 17, 1906, and in the hereinbefore mentioned co-pending application of Joseph Becker.

For convenience, the present description will be confined to this use of the invention; features of construction and operation are, however, capable of other valuable applications, consequently, the scope of the invention is not confined to the specific use and specific embodiment herein described as an illustrative example.

Referring to Figure 1 of the drawings, there is illustrated a fragment of a coke oven battery or plant of the by-product type, which plant embodies in its construction regenerators designated generally at 11 and having sole channels 12 that communicate at their outer ends with flow boxes 13. Each flow box is for the purpose of directing gaseous media into the regenerator, when the latter is operating for in-flow, and, on reversal of the flow, for directing the waste gases from the out-flow operating regenerator into an exhaust channel 14 by means of which the interior of said flow box may be placed in communication with the usual stack tunnel, not herein illustrated, but fully set forth and described in the prior patent and co-pending application above identified.

The present invention is chiefly concerned with the valve construction employed in the flow box 13 for shutting off the latter from communication with the exhaust passage 14 and the stack tunnel, when said flow box 13 and its communicably connected regenerator 11 are operating for in-flow. As shown, the flow box embodies in its construction a hollow

casing 15 provided with an upper valve chamber 16 that is communicably connected through a port 17 with a lower valve chamber 18. The lower valve chamber 18 is directly connected with the exhaust channel 14 through a port 19. With this construction gaseous media, in order to reach the exhaust channel 14 from the main or upper valve chamber 16 of the flow box, must first traverse the lower valve chamber 18. In the bottom of the said upper valve chamber 16, there is provided a seat 20 and in the bottom of the lower or auxiliary valve chamber 18 a similar seat 21.

15 The valve of the present invention is designed to close both the port 17 of the main valve chamber 16 and the port 19 of the lower auxiliary valve chamber 18, when said valve is in closed position. The valve embodies in 20 its construction a vertical valve stem 22, provided at its lower end with a horizontal valve body of the mushroom variety, such as the plate member 23, for cooperation with the upper valve seat 20, and also with a lower 25 horizontal mushroom valve body 24 similar to the valve body 23. The lower valve body 24 co-operates with the valve seat 21 of the auxiliary valve chamber 18, and as shown, is suspended from the upper valve body 23, so 30 as to be raised or lowered by the raising or lowering movement of said upper valve body, by means of flexible connections, such as the short chains 25. These flexible connections 35 are longer than the distance between the upper and lower seats 20 and 21, so that when the valve is in closed position, the lower valve body 24 rests on its seat 21 by its own weight and independently of the seating of the upper valve body 23. Consequently, the 40 flow box 13 will be cut off from the exhaust channel 14, by the independent seating of the lower valve body 24, should the upper valve body 23 not seat tightly, from any cause, such as a possible short stroke, or accidental sticking of its operating mechanism 45 hereinafter described.

In coke oven operation, it is necessary to maintain a pressure differential between the exhaust channel 14 and the interior of the flow 50 box 13, in order to effect the discharge through the channel 14 of the waste gases from the regenerator 11, when said regenerator and flow box are operating for out-flow. 55 With the double valve chamber and valve construction of the invention, the security against leakages past the seated valve bodies 23, 24 is greatly augmented, not only by reason of the more tortuous passage through 60 which leaking gases must pass, but also by reason of the auxiliary valve chamber 18 in which the pressure will be mediate that of the relatively high pressure in the upper valve chamber 16 and the relatively low pressure in 65 the exhaust channel 14, so that differences in

pressure on the opposite sides of each valve body 23, 24 are minimized.

The following mechanism may be employed for opening and closing the valve: As shown, the stem or shank 22 is provided with upper and lower collars 26 and 27, between which the shank is encircled by the outer end of an operating lever 28 fastened on a short or stub shaft 29. Also secured to the stub shaft 29 is the valve-operating arm 30, that 70 may be swung to open or close the valve, by means of the usual operating cable, such as is disclosed in the hereinbefore mentioned co-pending application of Joseph Becker. Below its fulcrum, the arm 30 is provided with a 75 depending finger 31 adapted to engage stops 32 and 33 for delimiting the swinging movement of the arm 30 in opposite directions. When said arm 30 is moved in one direction, the lever 28 is elevated to engage the upper collar 26 on the shank 22 to elevate both valve bodies 23 and 24 and open the valve. On reverse movement of the said arm 30, the lever 28 is lowered permitting the valve to close.

The flow box illustrated in the accompanying drawing may be employed alternatively for the in-flow of air into the regenerator 11. For this purpose, said flow box is provided with a lid 34 and lid-operating mechanism 35. When, however, the flow box is employed for in-flow of fuel gas, the lid 34 is fastened tightly on the top of the flow box by means of clamps 36. Fuel gas or other gaseous media may be directed into the interior of the flow box through port 37.

The invention as hereinabove set forth is embodied in a particular form of construction, but may be variously embodied within the scope of the claims herein made.

I claim:

1. A flow box, for regenerative heating structures, having an upper valve chamber connected by a port with a lower valve chamber to constitute a continuous passage for the gas flow, the said lower valve chamber being connected by a port with an exhaust channel; vertically movable mushroom valve bodies for respectively opening or closing the ports of said upper and lower chambers; flexible means connecting said valve bodies together, said flexible means being greater in length than the distance between the points on which the respective valve bodies seat, whereby the lower valve body may seat independently of the seating of the upper valve body; and mechanism operatively connected with said upper valve body for raising and lowering both said valve bodies; substantially as specified.

2. A flow box, for regenerative heating structures, having a main valve chamber connected by a port to an auxiliary valve chamber to constitute a continuous passage for the gas flow, the said auxiliary valve chamber being also connected by a port with an ex-

haust channel and acting to interpose between said main chamber and said valve chamber a pressure mediate that of the main valve chamber and the exhaust channel; individual valve bodies for opening and closing the ports of both said valve chambers; and an operating mechanism common to both said valve bodies; substantially as specified.

3. In a valve construction for flow boxes adapted for use with regenerative coke ovens in combination: a regenerator sole channel; an exhaust channel in which during normal operation is maintained a lower pressure than in the regenerator sole channel, whereby gaseous media may flow from said regenerator sole channel to said exhaust channel, when the regenerator is operating for out-flow; a flow box communicably connected with said regenerator sole channel and having a main valve chamber connected by a port with an auxiliary valve chamber, the said auxiliary valve chamber being also connected by a port, in series relation to the aforesaid port, with said exhaust channel and acting to interpose between said regenerator and said exhaust channel a pressure mediate that of the regenerator sole channel and the exhaust channel; and valve means for contemporaneously closing the ports of both said valve chambers; substantially as specified.

4. A valve construction, for the purpose herein set forth, comprising, in combination: a flow box provided with an upper valve chamber connected by a port with a lower valve chamber to constitute a continuous passage for the flow through the valve, the said lower valve chamber also having a port; vertically movable mushroom valve bodies for respectively opening or closing the ports of said upper or lower chambers; flexible means connecting said valve bodies together, said flexible means being greater in length than the distance between the points on which the respective valve bodies seat, whereby the lower valve body may seat independently of the seating of the upper valve body; and mechanism operatively connected with said upper valve body for raising and lowering both said valve bodies; substantially as specified.

5. A valve construction, for the purpose herein set forth, comprising, in combination: a flow box having a main valve chamber connected by a port with an auxiliary valve chamber to constitute a continuous passage for the flow through the valve, the said auxiliary valve chamber also having a port, in series relation to the aforesaid port; valve bodies for respectively opening or closing the ports of said valve chambers; means connecting said valve bodies together for permitting one of said valve bodies to seat independently of the other; and mechanism operatively connected with the latter valve body for operat-

ing both said valve bodies; substantially as specified.

6. A valve construction, for the purpose herein set forth, comprising, in combination: a flow box having a main valve chamber and an auxiliary valve chamber constituting a continuous passage for the flow through the valve; mushroom valve bodies for respectively controlling the flow in series through said chambers; means connecting said valve bodies together for permitting one to seat independently of the other, and means for raising and lowering both said valve bodies; substantially as specified.

In testimony whereof, I hereunto affix my signature this 31 day of August, 1921.

JOSEPH VAN ACKEREN.
